CLAIM

The ornamental design for a thermostat, as shown and described.

DESCRIPTION

FIG. 1 is a front perspective view of a thermostat showing our new design;

FIG. 2 is a front elevation view thereof;

FIG. 3 is a rear elevation view thereof;

FIG. 4 is a left side view thereof;

FIG. 5 is a right side view thereof;

FIG. 6 is a bottom plan view thereof;

FIG. 7 is a top plan view thereof;

FIG. 8 is a second front perspective view thereof; and,

FIG. 9 is a second front elevation view thereof.

The broken lines of even length illustrate portions of the thermostat that form no part of the claimed design.

A characteristic feature of the design resides in the portion shaded with diagonal line shading shown in front elevation and perspective views which is a partially reflective, partially transmissive mirror element, which is also known as a half-mirror.
